CLAIM

The ornamental design for a honey bottle, as shown and described.

DESCRIPTION

FIG. 1 is front elevational view of a honey bottle, showing my new design;

FIG. 2 is a rear elevational view of the bottle shown in FIG. 1;
FIG. 3 is a left front perspective view of the bottle shown in FIG. 1;

FIG. 4 is a right side elevational view of the bottle shown in FIG. 1, the left side being a mirror image; and,

FIG. 5 is a top plan view of the bottle shown in FIG. 1.

The broken lines shown are for illustrative purposes only and form no part of the claimed design.
